UNITED STATES PATENT OFFICE

JOHN E. ADAMSON AND JOHN EDGAR ADAMSON, OF POMONA, CALIFORNIA

ORCHARD HEATER

Application filed January 14, 1931. Serial No. 508,748.

The present invention relates to orchard heaters used in protecting orchards against frost.

An important object of the invention is to provide a device of this nature which is simple in construction, and in which solid fuel, such as briquettes may be used.

Another very important object of the invention resides in the provision of a device by which the natural upward draft of the products of combustion is checked, and in which means are provided to so deflect the products of combustion as to facilitate frost prevention over the largest area possible.

Another very important object of the invention resides in the provision of a device of this nature which is thoroughly efficient and reliable in use and otherwise well adapted for the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a side elevation of the device embodying the features of our invention.

Figure 2 is a top plan view thereof.

Figure 3 is a horizontal section taken substantially on the line 3-3 of Figure 1.

Figure 4 is a vertical section taken substantially on the line 4-4 of Figure 1.

Figure 5 is a sectional elevation of the device with the snuffer thereover, and

Figure 6 is a horizontal section therethrough taken substantially on the line 6-6 of Figure 5.

Referring to the drawings in detail it will be seen that the numeral 5 denotes a hollow body herein shown as cylindrical and formed with a plurality of spaced annular series of openings 6. Between the bottom pair of series 6 there is pressed inwardly an annular bead or shoulder 7 on which rests a grate disk 8 having a plurality of perforations 9. At the bottom of the cylinder 5 there is an outwardly projecting annular flange 10. An outwardly directed annular flange 11 is

formed at the top of the cylinder 5. A cover 12 has its longitudinal edges bent under itself as at 14 to form grooves to slide over the flange 11. One end of this cover has a V-shaped notch 15 formed thereon. A downwardly projecting stop 16 is formed at the other end of the cover. The numeral 17 denotes a cylinder the top end of which is closed as at 18. The cylinder 17 is of larger diameter than the cylinder 5 and may be placed over the cylinder 5 for snuffing out the fire when desired. The draft is controlled by the adjustment of the cover 12 as will be quite apparent.

The cover 12 may be dispensed with, and the draft controlled progressively by the series of openings 6 as the fire burns down, through the medium of a cylinder 17 that is adapted to be disposed concentrically of cylinder 5, and which is also of a diameter greater than the cylinder 17 may be retained at any desired fixed adjustment through the medium of a spring pressed latch rod 19 operable in a guide sleeve 20 provided therefor, on the wall of cylinder 17 adjacent the lower end of the cylinder. The inner end of rod 19 is adapted to project into one of the openings of any selected series of openings 6 for retaining the cylinder 17 in a fixed adjusted position.

From the above detailed description it will be seen that we have devised a heater which is exceedingly simple in its construction, inexpensive to manufacture, strong and durable, having its parts arranged for ease of assembly and disassembly and it will also be noted that we have devised a snuffer which may be easily and quickly placed over the heater to snuff out the fire when desired.

It is thought that the construction, utility and advantages of this invention will now be quite apparent to those skilled in the art without a more detailed description thereof.

The present embodiment of the invention has been described in considerable detail merely for the purposes of exemplification since in actual practice it attains the features of advantage enumerated as desirable in the statement of the invention and the above description.

Having thus described our invention, what we claim as new is:

1. In an orchard heater of the class described, a cylindrical casing having a plurality of spaced annular series of openings, an inwardly pressed bead formed in the casing between the lower pair of series of openings, a perforated disk resting on the bead, an annular flange projecting from the bottom end of the casing, a snuffer including a cylinder with a closed top, said cylinder being adapted to receive the casing with the lower edge of the member resting on the flange.
2. In a heater of the class described, a casing opened at its top, and provided on its peripheral wall with vertically spaced annular series of perforations, closure means for the open top of the casing including means for controlling the series of openings, to thereby control the draft progressively through the length of the casing.
3. In a heater of the class described, a casing provided with a vertical series of relatively spaced openings, means shiftable axially of the casing for controlling said openings to thereby progressively control the draft, and means for securing said member at the desired adjustment.
4. In a heater of the class described, a casing, provided with vertically spaced circular series of openings, a cylinder circumjacent the casing, and means carried by the cylinder and engageable with the casing for securing the cylinder at the desired vertical adjustment relative to the casing.

In testimony whereof we affix our signatures.

JOHN E. ADAMSON.
JOHN EDGAR ADAMSON.
